Watson E. Coleman
Atty

UNITED STATES PATENT OFFICE.

OSCAR KINCAID, OF HAZARD, KENTUCKY.

RAIL FASTENER.

Application filed April 26, 1924. Serial No. 709,215.

To all whom it may concern:

Be it known that I, OSCAR KINCAID, a citizen of the United States, residing at Hazard, in the county of Perry and State of Kentucky, have invented certain new and useful Improvements in Rail Fasteners, of which the following is a specification, reference being had to the accompanying drawings.

10 This invention relates to rail fasteners and more particularly to a rail fastener adapted for use in securing the rails of mine railways in position to the metallic ties thereof.

15 A further object of the invention is to provide a device of this character which is readily shiftable to accommodate rails of different widths and having flanges of different sizes and in which the adjustment necessary to alteration can be accomplished 20 by the use of the ordinary trackman's hammer and without the use of any other tools whatever.

25 These and other objects I attain by the construction shown in the accompanying drawings, wherein for the purpose of illustration is shown a preferred embodiment of my invention and wherein:—

30 Figure 1 is a plan view showing a tie having rail fasteners constructed in accordance with my invention, the rail fastener at one end of the tie being shown in position to hold the rail in applied position and at the other end of the tie being shown in position to permit removal of the rail;

35 Figure 2 is an enlarged vertical sectional view taken through the fasteners, tie and rail;

40 Figure 3 is an inverted perspective of one of the rail fasteners removed;

45 Figure 4 is an enlarged plan view of one of the fasteners.

Referring now more particularly to the drawings, the fastener comprises a hub portion 10 having a flat lower face and having radiating therefrom a plurality of wings 11. Two of these wings are diametrically opposed to one another and the remaining wings all lie to one side of the hub with respect to these aligned wings. The wings 50 11 have their under surfaces shaped to abut the lower portion of the web 12 of a rail and the upper and outer surface of the base 13 thereof at the same side of the rail, these wings being under-cut to fit against rails of 55 different sizes.

In the use of the device, the fasteners are secured to the metallic tie 14 by means of rivets passing through the tie and through a central opening 15 formed in the hub portion 10 of the fastener. The fasteners are 60 arranged in pairs directly opposing one another and are so spaced that when any corresponding pair of wings is aligned the distance between two fasteners will accommodate a rail of a given weight. These 65 wings are each marked upon the upper surfaces thereof to designate what weight of rail they are designed to coact with as, in the present instance, by applying indicia 16 each giving the weight of the rails with 70 which that particular wing is adapted to coact. When it is known, for example, that a twenty-five pound rail is to be applied to the tie, the rail is simply placed in position between the fasteners and the fastener rotated 75 by tapping with the usual trackman's hammer until the proper wings are aligned, at which time the rail will be very firmly held in position upon the tie and exactly centered between the fasteners. One side face of the 80 rail fastener being flattened, by aligning these side faces with the side edges of the rails the rails are cleared by the fasteners and may be vertically elevated for removal. Where adjoining ends of a rail are to be applied to the same tie, two pairs of the 85 fasteners may be secured to the tie at the side at which the joint is to be made.

It will be obvious that a fastener of this type becomes a permanent part of the tie 90 and is shifted with the tie, permitting application of any desired size of rail to the tie and eliminating the necessity of separately transporting the rail fasteners and employing a number of tools in such transportation. It will furthermore be obvious that the construction as hereinbefore set forth is capable of a certain range of change and modification without materially departing from the spirit of my invention and I accordingly do not limit myself to such specific structure except as hereinafter claimed.

I claim:—

In combination with a metallic mine car rail tie, pairs of opposed rail fasteners permanently and rotatably secured to said tie and each including a plurality of radially directed arms, said arms being adapted as to length and the contour of the under surfaces thereof for coaction with rails of dif- 110

ferent weights, said arms each bearing indicia indicating the weight of the rail with which they are adapted to coact, two of said arms being diametrically aligned with the remainder of the arms lying at one side of the pivot point from said aligned arms whereby a flat side is provided upon the

fastener, the arrangement of the flat sides of the fasteners in opposition to one another permitting vertical removal of a rail held therebetween. 10

In testimony whereof I hereunto affix my signature.

OSCAR KINCAID.
